US0D1070710S

(12) **United States Design Patent** (10) **Patent No.:** **US D1,070,710 S**
Bellevin (45) **Date of Patent:** **** Apr. 15, 2025**

(54) **VEHICLE WHEEL, TOY VEHICLE WHEEL, AND/OR REPLICAS THEREOF**

(71) Applicant: **Bayerische Motoren Werke Aktiengesellschaft**, Munich (DE)

(72) Inventor: **Justin Bellevin**, Munich (DE)

(73) Assignee: **Bayerische Motoren Werke Aktiengesellschaft**, Munich (DE)

(**) Term: **15 Years**

(21) Appl. No.: **29/921,917**

(22) Filed: **Dec. 20, 2023**

(30) **Foreign Application Priority Data**

Jun. 27, 2023 (DE) 402023100431.4
